UNITED STATES PATENT OFFICE

2,475,992

GARMENT HANGER

Hans M. Schliestedt, Chicago, Ill.

Application March 1, 1948, Serial No. 12,270

3 Claims. (Cl. 223—91)

1

My invention relates to garment hangers, an important object of which is to provide a garment hanger that will securely support, by means of frictional engagement of its parts, a garment such as a pair of trousers or a skirt.

A further object of my invention is to provide a garment hanger, formed of a single length of wire bent into a grill-like formation and having a gate formation between which the end of a garment may be securely held by releasable snap locking means, and having formed at its top a hook means for suspending the garment hanger and garment to a clothes rack or wall hook.

A still further object of my invention is to provide tit-like formations in the wire gate which, in the closed position, project into and between several of the grills and thereby provide an even more secure frictional engagement for the garment therebetween.

A still further object of my invention is to provide a garment hanger that may be formed by bending a single length of wire into its various parts and which requires no welding or other attaching means to hold it together.

Other objects and advantages inherent in my invention will become readily apparent from the ensuing description and the accompanying drawings, in which like parts are designated by like numerals, and in which:

Fig. 1 represents a perspective view of my invention shown in a closed position and holding the end of a garment, which is shown in dotted lines.

Fig. 2 represents the top view of a portion of my invention shown looking in the direction of arrows 2—2 on Fig. 1.

Fig. 3 is a cross-sectional view taken substantially on the line 3—3 of Fig. 2.

Referring to the illustrations, my invention is generally designated 4 and consists of a single length of wire designated 5. The end of the wire 5 is bent into a hooked formation at 6, the bottom of which is bent downwardly or vertically at 7, and then bent at approximately a 60° angle to form the right-hand top support portion 8. The outer end of the top support portion 8 is bent downwardly at 9 to form a part of the right-hand side support; the end of the side support 9 is formed into a knot-like loop 10, which is curved around the side portion 9 to form the top 11 of

2

a gate-like formation, generally designated 28, and having a left-hand side 13 and a bottom 12. The side 13 of the gate 28 is arcuately bent at 14 to engage the side 20 of a grill formation 17; the right end of the bottom 12 of the gate 28 being bent upwardly to form the right support side 15 and is arcuately bent at 16 to pass through the previously described loop 10.

At the arcuate bend 16, the wire 5 is formed downwardly into the right-hand side of a grill 17, which consists of a number of vertical portions 18 continuously interconnected by arcuate bends 19. The left-hand vertical portion 20 being offset at 21 to act as an engaging means for the arcuately bent side 13 of the gate 28. The bottom offset bend 21 of the grill 17 is arcuately bent at 22 to form the left-hand side support 23 for the clothes hanger and is bent in a 60° angle at 23 to form the left-hand top support 24, which is bent and coiled at 25 around the vertical portion 7 of the hook 6, completing the construction.

The wire of the top 11 and the bottom 12 of the gate 28 is bent into a number of tit-like formations which are so located that, when the gate 28 is closed against the grill 17, the tit formations 26 will project into and beyond the spaces 30 formed by the sides 18, and will provide an increased clamping arrangement for a garment 27 disposed intermediately therebetween.

The arcuate bend 16 of the gate 28 being securely held by the loop 10 of the side support 9 acts as a spring-like hinge for the gate 28 and, to use the garment hanger, the arcuately bent end 13 of the gate 28 is disengaged from the end 20 of the grill 17 and swung outwardly, as shown by dotted lines in Figs. 1 and 2.

A garment 27 is placed between the grill 17 and the gate 28. The gate 28 is now closed by re-engaging the arcuately bent side 13 with the end 20 of the grill 17. In this position, the top 11 and bottom 12 of the gate 28, together with the tit-formations 26 thereon, will hold a garment 27 firmly in place between the gate 28 and the grill 17, and the garment may be hung upon a clothes rack or hook by means of its hooked formation 6.

It will be noted that this garment hanger is constructed of a single length of wire which is formed and bent into its various parts and that

no welding or other attaching means are used whatsoever.

The disclosure hereinabove may be departed from in keeping with general structural equivalents, provided they are embraced within the purview of the limitations set forth and defined in the appended claims.

Having thus disclosed and revealed my invention, what I claim as new, and desire to secure by Letters Patent, is:

1. A garment hanger made of one piece of wire comprising, a hanger hook portion connected to an angular support portion, the said angular support portion continuing to form an articulate loop portion further continuing to form a gate portion interconnected by an offset snap locking portion, the terminus of the said gate portion being formed into an upright portion the end of which is articulately secured through the said loop portion and continuing to form a sinuously formed portion cooperatively associated with the said gate portion to clamp a garment therebetween, the terminus of the said sinuously formed portion being formed into a mating offset snap locking portion adapted to releasably engage the said first-mentioned offset snap locking portion, the said second-mentioned offset snap locking portion continuing to form a second upright portion oppositely disposed to the said first-mentioned upright portion, the said second-mentioned upright portion continuing to form a second angular support portion to complete the hanging support section for a coat-like garment, the terminal portion of the said second-mentioned angular portion being coiled about the neck portion of the said hook portion.

2. A garment hanger made of one piece of wire comprising, a hanger hook portion connected to an angular support portion, the said angular support portion continuing to form an articulate loop portion further continuing to form a gate portion interconnected by an offset snap locking portion, the terminus of the said gate portion being formed into an upright portion the end of which is articulately secured through the said loop portion and continuing to form a sinuously formed portion cooperatively associated with the said gate portion to clamp a garment therebetween, the terminus of the said sinuously formed portion being formed into a mating offset snap locking portion adapted to releasably engage the said first-mentioned offset snap locking portion, the said second-mentioned offset snap locking portion continuing to form a second upright portion oppositely disposed to the said first-men-

tioned upright portion, the said second-mentioned upright portion continuing to form a second angular support portion to complete the hanging support section for a coat-like garment, the terminal portion of the said second-mentioned angular portion being coiled about the neck portion of the said hook portion, the said gate portion in association with the said sinuously formed portion being adapted to releasably clamp a garment therebetween when both the said offset snap locking portions are secured.

3. A garment hanger made of one piece of wire comprising, a hanger hook portion connected to an angular support portion, the said angular support portion continuing to form an articulate loop portion further continuing to form a gate portion interconnected by an offset snap locking portion, the terminus of the said gate portion being formed into an upright portion the end of which is articulately secured through the said loop portion and continuing to form a sinuously formed portion cooperatively associated with the said gate portion to clamp a garment therebetween, the terminus of the said sinuously formed portion having recesses and being formed into a mating offset snap locking portion adapted to releasably engage the said first-mentioned offset snap locking portion, the said second-mentioned offset snap locking portion continuing to form a second upright portion oppositely disposed to the said first-mentioned upright portion, the said second-mentioned upright portion continuing to form a second angular support portion to complete the hanging support portion for a coat-like garment, the terminal portion of the said second-mentioned angular portion being coiled about the neck portion of the said hook portion, the said gate portion being provided with tit formations engaging the said recesses in the said sinuously formed portion to more effectively hold a garment supported between the said sinuously formed portion and the said gate portion.

HANS M. SCHLIESTEDT.
